UNITED STATES PATENT OFFICE.

LEONHARD ARENT, OF BUFFALO, NEW YORK.

STREET-SWEEPER.

1,177,083.

Specification of Letters Patent. Patented Mar. 28, 1916.

Application filed May 21, 1915. Serial No. 29,523.

To all whom it may concern:

Be it known that I, LEONHARD ARENT, a subject of the Czar of Russia, residing at Buffalo, in the county of Erie and State of New York, have invented certain new and useful Improvements in Street-Sweepers, of which the following is a specification.

This invention relates to new and useful improvements in street sweepers.

10 An object of the present invention is to provide a street sweeper in which the rear supporting wheels for the sweeper frame constitute the driving means for the sweeper roller with means for raising and lowering 15 the sweeper roller into and out of operating position.

20 A further object of the invention is to provide a street sweeper in which the supporting wheels for the sweeper frame constitute the driving means for the sweeper roller with a compartment or trough positioned adjacent the sweeping roller adapted to receive the dirt gathered by the roller and to further provide a box-like receptacle 25 pivotally supported on the rear axle and into which the dirt received in the trough may be delivered by workmen riding in the dirt-receiving compartment.

30 A still further object is to provide a street sweeper including an automatically driven sweeping roller in combination with a dirt-receiving compartment and a movable guide, the guide being vertically adjustable and limited in its downward movement by 35 the adjusting means but which may be permitted to rise or be elevated into proximity with the brush to compensate for unevenness of the ground or obstructions thereon.

With the above objects in view and others 40 that will appear as the nature of the invention is better understood, the same consists in the novel combination and arrangement of parts to be hereinafter more fully described, illustrated in the accompanying 45 drawings, and set forth in the appended claim.

In the accompanying drawings forming part of this application and in which like designating characters refer to corresponding parts throughout the several views:— Figure 1 is a side elevational view of a street sweeper built in accordance with the present invention. Fig. 2 is a top plan view of the same. Fig. 3 is a longitudinal sectional

view of a portion of the device, and, Figs. 4 and 5 are detail sectional views of portions of the device taken on lines IV—IV and V—V respectively, of Fig. 1.

Referring more in detail to the accompanying drawings, the reference numeral 10 designates in general the street sweeper illustrated as including a forward platform section 11 to which are secured the rearwardly-extending side rails 12, which rails are preferably formed of angle irons, more clearly shown in Fig. 5, which add strength and rigidity to the machine, with the result that a sweeper of extremely light weight and one that will be inexpensive to manufacture will be obtained. A seat 13 is mounted on the forward platform 11 for the use of the driver. The supporting means for the frame includes front wheels 14 and rear wheels 15, the front wheels having the usual fifth wheel connection 16 to the forward platform 11 and provided with the usual draft devices 17. A rear axle 18 is journaled through the side bars 12 with the supporting wheels 15 spaced inwardly of the side bars, while one of the wheels is fixed to the axle 18 with the other one journaled on said axle.

The receptacle into which dirt is finally delivered includes a box-like structure 19 having a fixed bottom wall and fixed side and front walls, with a rear end wall or tail gate 20 pivoted at its upper end as at 21 to the side walls of the receptacle while a pin 22 projecting inwardly from the lower ends of the side walls limits the swinging movement of the end gate 20. The receptacle 19 is pivotally mounted on the axle 18 by means of angle plates 23, one leg of each angle plate 23 being secured to the bottom wall of the receptacle 19 adjacent the side edges thereof while the other legs are journaled on the rear axle 18 as is clearly shown in Fig. 3. The receptacle 19 is pivoted off-center to the axle 18 so that the same will have a natural tendency to swing downwardly at its rear end and in order to hold the same in the upright position as shown in Fig. 3, I have provided locking means for the forward end of the receptacle. This locking means includes a cross bar 24 positioned transversely of the side bars 12 and preferably of angle-iron construction as shown in Fig. 3, upon which the forward end of the receptacle 19 is adapted to rest.

A centrally-positioned pin projects from the bar 24 and is adapted to be engaged by the swinging clasp 25 carried by the front wall of the receptacle 19, thereby to hold the 5 said receptacle in horizontal position.

The sweeping mechanism including the brush roller and the carrier for initially receiving the dirt or sweepings is positioned between the forward platform 11 and the 10 dirt receptacle 19, and is positioned adjacent the ground as illustrated, and includes a receptacle or compartment for receiving the dirt from the sweeper which embodies a front wall 26, side walls 27 and a bottom 15 wall 28, these parts being preferably formed of sheet metal and supported on the side bars 12 by clamping bands 29. A guide adapted to direct the dirt gathered by the brush roller is designated 30 and is hinged 20 to the lower rear edge of the bottom wall 28 of the dirt receptacle as at 31 while the end walls of the guide 30 at all times overlap the side walls 27 as is indicated in Fig. 3 to prevent the dirt from falling from the 25 guide. The means for adjusting the height of the guide with respect to the ground includes arms 32 hinged at their lower ends as at 33 to the guide 30 while their upper ends are provided with a series of spaced 30 openings 34 into which pins 35 are received and these pins being positioned upwardly of the side bars 12 rest thereon and will permit the guide to rise at will but limit the lowering movement thereof. A brush roller 36 is positioned between the rear wheels 35 and the guide 30 and has its ends journaled in the free ends of the links 37, the other ends of the links being pivotally mounted as at 38 between the end walls 27 of the dirt 40 receptacle, and the forward retaining bands 29. It will be noted that the links 37 extend between the end walls 27 and rear retaining bands 29 as is indicated in Fig. 4 which constitute guides for the links.

45 A shaft 39 is journaled at its ends in bearings 40 supported on the side rails 12 and substantially in vertical alignment with the brush roller 36, with the ends of the shaft extending laterally of the side rails. The 50 axle of the brush roller 36 is connected at its ends to the shaft 39 by ropes or cables 41 connected at one end to the brush roller and at their other ends to the extended shaft ends 39 upon which the same are wound.

55 A toothed wheel 42 is fixed on each end of the shaft 39 and is adapted to be engaged by a spring-pressed sliding latch 43 mounted on the side rail 12 to hold the gear and shaft in fixed position with the brush roller elevated by the ropes 41 at the desired 60 height. A hand wheel 44 is fixed to the shaft 39 inwardly of the side bars 12 and by which the shaft may be operated to raise and lower the brush roller.

65 The rear axle 18 constitutes the driving

means for the brush roller and has one end thereof projecting laterally of one of the side bars 12 and upon which is fixed a gear wheel 45. Depending arms 46 are carried by the side rails 12 and are spaced forwardly 70 of the front wall 26 of the dirt receptacle and have journaled therein a pair of shafts 47 and 48 projecting laterally thereof. A small gear 49 is fixed on one end of the shaft 47 and is driven by the rear axle gear 45 75 through the medium of the sprocket chain 50. A larger gear 51 is fixed on the shaft 47 inwardly of the smaller gear 49 and is in mesh with a lantern gear 52 fixed on the shaft 48. A small gear 53 is fixed to each 80 extended end of the shaft 48 and has sprocket chains 54 engaging therewith, which sprocket chains also engage gear wheels 55 carried by each end of the brush axle and by which the brush 36 is revolved. 85

In the operation of the machine, and in the forward movement thereof the rear axle 18 is adapted to drive the sprocket chain 50, which in turn drives the shaft 47, and this shaft being connected with the shaft 48 90 by the gear and lantern wheels 51 and 52 respectively, the said shaft 48 is adapted to be revolved and communicates rotary motion to the brush roller 36 by the connecting sprocket chain 54. The guide 30 may 95 be raised and lowered by the adjusting means 34 and 35, while the brush roller 36 may be raised and lowered by the elevating mechanism more clearly shown in Fig. 5 and hereinbefore specifically referred to. 100 The driver of the machine is upon the forward platform 11 while a workman is carried in the dirt compartment 26 and dirt received in the compartment by the brush 36 may be shoveled into the dirt receptacle 105 19 by the workman. The end gate 20 of the receptacle 19 may be swung on its pivot 21 for purposes of emptying the same, or the entire receptacle may be moved on its pivotal connection with the rear axle 18 by releasing the fastening device 25. 110

From the above detailed description of the machine, it is believed that the operation and construction thereof will be readily apparent, and while I have herein shown the preferred embodiment thereof, it is nevertheless to be understood that various forms and modifications thereof may be made without departing from the spirit and scope of the invention as claimed. 120

What I claim as new is:—

A street sweeper including a frame having a forward platform and rearwardly-extending side bars, a rear axle journaled at the rear ends of the side bars, supporting wheels for the axle, front supporting wheels for the front platform, a dirt receiving compartment located between the forward platform and the rear axle, a guide hinged to the rear end of said dirt com- 130

partment, links connected at their lower ends to said guide and adjustably connected at their upper ends to the side bars, a pair of links pivoted at their forward ends to said dirt compartment, a brush roller journaled in the rear ends of said links and positioned between the rear supporting wheels

and the guide, a winding shaft journaled on said frame, ropes wound on said shaft and connected to said brush roller, and driving means for the brush roller extending between the brush and the rear axle. 10

In testimony whereof I affix my signature.
LEONHARD ARENT.
